The ornamental design for a beverage container, as shown and described.

DESCRIPTION

FIG. 1 is a front elevational view of a beverage container showing my new design, the rear elevational view being identical;

FIG. 2 is a left side view thereof, the right side view being identical;

FIG. 3 is a top plan view thereof;

FIG. 4 is a bottom plan view thereof;

FIG. 5 is a perspective view thereof;

FIG. 6 is an exploded perspective view of the three components, body, seal and lid;

FIG. 7 is a cross-sectional view taken along line 7-7 of FIG. 5;

FIG. 8 is a perspective view of the lid portion shown separately to show aspects of the design that may not be apparent in the other views; and,

FIG. 9 is another perspective view thereof.

The broken lines in the drawings depict portions of the beverage container that form no part of the claimed design.
